UNITED STATES PATENT OFFICE.

ALPHONSE HUILLARD, OF SURESNES, FRANCE.

DRYING APPARATUS.

1,410,063.

Specification of Letters Patent. Patented Mar. 21, 1922.

Application filed August 13, 1913. Serial No. 784,564.

(GRANTED UNDER THE PROVISIONS OF THE ACT OF MARCH 3, 1921, 41 STAT. L., 1313.)

To all whom it may concern:

Be it known that I, ALPHONSE HUILLARD, citizen of the Republic of France, residing at Suresnes, in the Republic of France, have 5 invented certain new and useful Improvements in Drying Apparatus, of which the following is a specification.

This invention relates to drying apparatus having sieve floors arranged one above 10 the other, and having apertures in the middle adjacent which are arranged transfer chambers which are provided with an arrangement which allows of the transfer of the material from one floor to another without allowing the hot gases rising upwards 15 from the bottom to pass through.

The invention relates more particularly to drying apparatus of the kind before mentioned, in which the transfer chambers are 20 divided by fixed radial walls into compartments, and are covered at the ends with rotary discs which are provided with slots displaced relatively to one another, so that a direct passage of the material from one 25 floor of the drying apparatus to the next, and consequently a free passage of the heated gases is prevented.

These end discs are mounted on a vertical central shaft passing through the apparatus and must always remain in close contact with the end edges of the transfer chambers in order that the apparatus may work reliably.

As, however, the vertical central shaft 35 under the action of the hot gases expands longitudinally considerably, it is necessary to arrange the end discs mounted on the shaft at a greater distance apart than corresponds to the depth of the transfer chambers, in order to obtain the space for play 40 between the discs and the respective ends of the transfer chambers necessitated by the variations in length of the shaft. This causes the chambers to be incompletely 45 closed against the passage of the gas current.

Now by this invention this disadvantage is avoided by the discs, instead of being mounted directly on the shaft, being mounted on sleeves or bushes which are 50 mounted on the central driving shaft in such a manner that they are not revoluble but are longitudinally displaceable, so that a close fitting of the discs on the end edges of the transfer nozzles can be maintained,

whilst allowing a free expansion of the 55 shaft.

The two end discs may either be mounted on a bush common to both or each independently on a separate bush.

In the first case the distance between the 60 adjacent sides of the two discs must correspond as far as possible exactly to the distance between the two ends of the transfer chambers in order to ensure both discs fitting closely on these ends. 65

In the second case each disc may be pressed independently by suitable means (springs, weighted levers or the like) against the end of the chamber or both discs may be drawn together by a spring, and thus 70 held in close contact with the ends of the chamber.

In many cases it is desirable, in drying apparatus of the kind mentioned, to be able to vary the distance of the scrapers, which 75 are arranged to rotate above the sieve floors, from the central shaft and the distance of the lower edge of the scraper from the sieve floor, also the inclination of the scoops or scrapers from a radial direction for the 80 purpose of altering the speed of movement of the material lying on the sieve floors towards the transfer chambers provided in the centre of the floors. In order to enable these alterations to be made rapidly and 85 easily in accordance with this invention, the scoops or scrapers are supported by the intermediary of scoop or scraper carriers adjustable on radial carrying arms fixed on the central driving shaft. The free ends 90 of the scraper carriers are formed as vertical bushes, in which the shafts of the scoops or scrapers can be fastened by means of clamping screws or the like.

The invention is illustrated in the accompanying drawings: 95

Figure 1 is a longitudinal section of the drying apparatus;

Figure 2 a longitudinal section on an enlarged scale of a chamber; and 100

Figures 3 and 4 are side views on an enlarged scale of a scraper or scoop with its holder;

Figure 5 is a fragmentary plan view showing more clearly the structure of the discs. 105

The material to be dried which is inserted through an upper aperture *a* passes on to the uppermost sieve floor *b* and is conveyed

towards the centre by the obliquely placed scrapers *c* continuing on to the slot *d* in the rotating discs *e* which cover the compartments of the transfer chambers. The dried material fills these compartments as the slot *d* in the rotating upper disc *e* successively gives admission thereto. The discharge of the dried material onto the floor situated beneath it is effected by the successive uncovering of the compartments by the rotating disc *g* when its slot *h* comes beneath the respective compartment, the latter being closed above by the solid part of the disc *e*, so that the hot gas can never pass directly through the compartments of the transfer chambers.

10 The material escaping from the chamber *f* falls on to a conical guide surface *i* and down the latter on to the outside edge of the next sleeve floor, whereupon the operations 15 previously described are repeated.

20 The two discs *e* and *g* are secured to the ends of a bush *l* mounted in the hub *k* of the transfer nozzle *f*, which bush is not revolubly but longitudinally displaceably mounted on the vertical central shaft *m*. For the object a key *n* which is movable in a longitudinal groove in the sleeve is provided on the shaft. The scrapers *c* arranged above 25 the sieve floors are connected by means of 30 displaceable scraper carriers *r* with radial arms *o* (Figure 3) fixed on the central shaft *m*. These scraper holders are fixed by means of clamp yokes *q* which can be drawn together by screw bolts *w* and allow the number 35 of the scrapers, their radial distance

from the central shaft, the inclination of the scrapers out of the radial direction, and the height of the lower edges of the scrapers from the sieve floors to be easily and rapidly altered, whereby it is possible to regulate 40 the speed of movement of the material to be dried over the sieve floors and to ensure the uniformity of the distribution of the material on the sieve floors.

Having now particularly described and 45 ascertained the nature of my said invention and in what manner the same is to be performed, I declare that what I claim is:

A drying apparatus having sieve floors arranged one above the other, and provided 50 with apertures in the middle leading to transfer chambers which are divided by radial walls into compartments and are covered at their ends by rotating discs provided with relatively displaced slots; in which these 55 discs are carried by bushes which are mounted on the vertical central shaft, in such a manner as to be longitudinally displaceable but not revoluble, in order to enable the discs to fit closely on the ends of the transfer 60 chambers, even when the central shaft expands longitudinally under the action of the hot gases.

In witness whereof I have hereunto signed my name this 17th day of July, 1913, in the 65 presence of two subscribing witnesses.

ALPHONSE HUILLARD.
